UNITED STATES PATENT OFFICE.

MAURITZ C. INDAHL, OF PHILADELPHIA, PENNSYLVANIA, ASSIGNOR TO LANSTON
MONOTYPE MACHINE COMPANY, OF PHILADELPHIA, PENNSYLVANIA, A CORPO-
RATION OF VIRGINIA.

TYPOGRAPHIC COMPOSING-MACHINE.

1,256,801.

Specification of Letters Patent. Patented Feb. 19, 1918.

Application filed August 4, 1916. Serial No. 113,178.

To all whom it may concern:

Be it known that I, MAURITZ C. INDAHL, a citizen of the United States, and a resident of Philadelphia, in the county of Philadelphia and State of Pennsylvania, have invented certain new and useful Improvements in Typographic Composing-Machines; and I do hereby declare the following to be a full, clear, and exact description of the same, reference being had to the accompanying drawings, forming part of this specification.

My invention relates to keyboard composing machines for producing record strips containing signals representing characters and spaces constituting justified lines of type. More particularly my invention relates to machines of this kind which embody automatically operative justification indicating devices and which also embody a repeat mechanism, that is, a mechanism, controlled for example by a special key, which produces a repetition of the signals for a given character the representative key of which is also operated.

Such composing machines having repeat mechanisms have proved to be of marked utility in the typographic composing art owing particularly to the great speed with which the repeat mechanism is capable of causing the automatic repetition of desired signals in the record strip. Commercial operation of these machines has shown, however, that during the operation of the repeat mechanism within the justification area, the justification indicating devices are subjected to undue wear and shock sufficient to threaten their early disintegration while the line measuring mechanism, always a part of such machines, is caused at times to function unreliably resulting in indications on the part of the justification indicating mechanism which are incorrect and the cause of erroneous justification signals in the record strip. These undesired results are traceable to the extreme speed with which the repeat mechanism acts and to the resistance encountered in setting the justification mechanism in motion. Whatever the causes of the defects referred to, it is the object of my invention, generally speaking, to produce a keyboard composing mechanism in which these defects are eliminated but in which the speed of the repeat action

is in no degree sacrificed. More specifically, the object of my invention is to so arrange and relate the repeat mechanism with respect to the automatically operating justification indicating mechanism that the latter is rendered inactive and unaffected by other mechanism while the repeat device is in operation. Other objects will be specifically pointed out or will otherwise appear in connection with the description of the embodiment of my invention shown in the accompanying drawings and presently to be described.

I have chosen for illustrating my invention a pneumatic keyboard composing machine of the general class of that shown in Patent No. 944,403, dated December 28th, 1909, and in its fundamental features the machine shown in the accompanying drawings is similar to the patented machine. The latter does not include, however, an automatically acting justification indicating mechanism, justification being there indicated by the actuation of a special key, manually operated, and the accompanying drawings show in this particular a device which is to a considerable extent similar to the justification indicating means of Patent No. 1,149,176, dated August 10th, 1915. A repeat mechanism is also shown herein which follows in its main features the mechanism of Patent No. 1,149,175, dated August 10th, 1915.

In connection with the following description reference will be made to the three patents above mentioned and the reference characters thereof or modifications of such characters will be employed as much as possible in order to assist in the identification of the parts corresponding with those shown in the patents. In the accompanying drawings,

Figure 1 is a vertical section of a keyboard machine.

Fig. 2 is an enlarged view of a portion of the device of Fig. 1 showing the air pressure chamber and valves, the repeat motor and associated parts.

Fig. 3 is a detail view, parts being in section, showing the justification indicator actuating elements and their connection with the air pressure chamber through a conduit governed by a justification control valve and the bar for operating said valve.

Fig. 4 is a front elevation of the measuring and justifying mechanism, certain well known parts being omitted and others being broken away.

5 Fig. 5 is a detail view of the repeat motor rocker frame, a character designating bar and a character designating valve.

Fig. 6 is a sectional elevation of a portion of the keyboard showing the forward 10 ends of various valve bars, the rocker frame of the repeat mechanism and adjacent parts.

Fig. 7 is a perspective view of the justification control bar and actuating devices, and

15 Fig. 8 is a side elevation, similar to Fig. 2, showing a modified justification control valve and operating elements therefor.

Like characters of reference in the several views indicate the same parts.

20 It is not necessary, in setting forth the present invention, to present a detailed description of the composing machine fully disclosed in Patent No. 944,405. It is sufficient for present purposes to designate and 25 identify some of the parts of such machine shown in Fig. 1, particularly those which are operatively or otherwise involved with the mechanism of the present invention. These parts, identified by reference charac-

30 ters which are in general the same as those found in the said patent, are as follows:— the keys 180, operating the keybars 177, the rock shafts 174, forming the connections between the keybars and the valve bars 173,

35 the valves 170, (Fig. 5) operated by said valve bars, the air chamber 161 containing air under pressure adapted to be admitted by the operation of the valves, to the corresponding cylinders of the pneumatic punch bar motor mechanisms to move the punch bar levers 17 upwardly and with them the punch bars 15; the line scale pointer 14' carried by the line scale rack 14 in mesh with the line scale pinion 7', secured to the 40 units wheel shaft upon which is also secured the units wheel 7 (Fig. 4) and the pinion 6', meshing with the motor rack 6, the latter being driven by the motor piston 4', operated by air under pressure in the motor cylinder 4; the paper feed motor cylinders 137 and 138 and the paper feed reversing valve 146.

45 The justification indicating mechanism shown in the accompanying drawings does not require to be described in detail. As to those parts thereof which are found in the disclosure of Patent No. 1,149,176 it will be sufficient to point out the more important of them so that the mechanism as a whole

50 and its operation may be clearly brought to mind. Reference is thus made to the gaging member 9 (Figs. 3 and 4) having rack teeth connected with the justification indicator 8 by the gearing 10; the pin 19 within

65 said member 9, adapted to abut at one end

the projection 115 of the abutment slide 9^a moved by the piston 4', when the justification area has been entered, the other end of the pin 19 abutting the fixed stop 22; the adjustable connection 21 between the pin 19 70 and the gaging member 9; and the cylinder 12 and the piston 13 therein, the piston rod 114 thereof also abutting the projection 115.

75 The motor for the justification indicating mechanism illustrated consists of the cylinder 25 (Figs. 1 and 3), the piston 24 therein, the piston rod 23 of which is provided with rack teeth meshing with a pinion of the gearing 10, the diametrically opposite side of which pinion also meshes with the rack 80 teeth of the gaging member 9. The cylinders 12 and 25 are connected together at all times by the pipes 28 and 117 and the latter is connected through a justification control valve, to be described hereinafter, with air 85 under pressure in the air chamber 161. It will be seen that when air under pressure is in the cylinders 12 and 25 the piston 13 will move or maintain the abutment slide against the motor piston 4', the piston 24 90 opposing the piston 13 but exerting less pressure on account of its smaller area. The displacement of the abutment slide against the resistance of piston 13 is accomplished by the piston 4' which being of the greatest 95 area, exerts the greatest pressure, and is followed at once by the positioning of the indicator mechanism operated from the piston 24 to bring the pin 19 again in contact with the abutment slide.

100 The repeat mechanism shown in the accompanying drawings follows after the general plan of that of Patent No. 1,149,175 but it contains departures therefrom as will appear from the following description. In 105 the machine shown the valve bars 173 or those of such valve bars which it is desired to have automatically repeat their functions, do not contact directly with the valve stems 170, but they are provided with members 110 which are normally moved in unison therewith but are under certain circumstances capable of an independent movement to effect the repeat action. As shown, in the accompanying drawings, the said valve bars 115 173 (Fig. 5) are provided at their inner ends with yokes 16^a, the lower ends of which extend down under and are guided by the bottom face of the rock shaft bracket connecting bar 17^a. These yokes are preferably 120 made of parallel members so as to be exceedingly light and between them there is pivotally mounted a bell crank lever 18^a, the upper arm of which projects into position to coöperate with one of the valve stems 125 170 whenever the valve bar is advanced, and the other arm of which projects parallel with the lower portions of the yokes, but extends beyond the same and is guided by the under face of the part 17^a, as well as by 130

the upper face of a repeat bar 19^a, to be presently described. Inasmuch as the movement of the bell crank lever on its pivot 20^a is normally prevented by the guiding faces between which the lower arm of the bell crank operates, a forward movement of the valve bar will result in a corresponding bodily forward movement of the bell crank and an operation of the appropriate valve 5 stem and valve. This construction of the valve bars is one which may be cheaply manufactured, is exceedingly light and in its operation does not impose upon the operator any appreciable additional labor, the latter feature being an important consideration in the machine, inasmuch as any additional labor imposed on the operator tends to decrease the speed of production.

Obviously, in such an arrangement should 20 the valve bar be advanced from the position shown in Fig. 8 to that shown in Fig. 5, and there held, as by keeping the key depressed, the valve may be operated by permitting the bell crank lever to move on 25 its pivot 20^a, and advantage is taken of this arrangement in effecting the repeat operation by providing for a rapid reciprocation of the repeat bar 19^a (see dotted lines in Fig. 5). The operation of the bell cranks on the 30 valve bars not advanced is prevented by permitting the upwardly extending arms of the bell cranks to seat against the front of the valve bar guide 17^b. Conveniently, the bell 35 crank levers are formed with projections 18^b which extend between the yokes 16^a to contact with the guide 17^b, as shown in Fig. 8.

In the preferred arrangement, the repeat bar 19^a, forms a part of a rocker frame 21^a pivotally mounted at 22^a on a bracket 23^a (Fig. 2) fastened to the connecting bar 17^a. The rocker frame 21^a is at one end provided with a rearwardly extending arm 24^a, (see Figs. 1, 2, 5 and 8) with which the repeat motor co-operates. The repeat motor, as in 45 the patent last above referred to, embodies generally in its construction a pair of oppositely disposed cylinders 25^a and 26^a in which pistons are mounted to reciprocate and between the proximate faces of which pistons 50 the end of the arm 24^a is located.

Pneumatic pressure for operating the pistons is supplied to the cylinders through ducts 52^a which lead from the paper feed cylinders 137 and 138, as shown in Fig. 1, 55 or from the valve 146 which supplies the cylinders 137 and 138, just as in said prior patent, and obviously when repeat action is desired, the pistons will be reciprocated and the repeat bar 19^a moved to oscillate the bell 60 crank lever or levers as desired.

In so far as the control of the pneumatic pressure for operating the repeat motor is concerned, the present mechanism does not differ from the mechanism of the said prior 65 patent, and corresponding arrangements are

shown for effecting this end in Fig. 1 which is in this respect similar to Fig. 1 of the said patent.

The repeat bar 19^a is normally held up against stops 19^b or in its elevated position 70 by a supporting latch 27^a, formed on a downwardly extending arm of the plate 28^a (Fig. 7), pivotally mounted on a shaft 30^a carried by an end bracket 31^a of the frame 23^a. A lever 29^a projects upwardly from the 75 plate 28^a and is adapted for the reception of the rear end of a stop rod 32^a (see Fig. 6) mounted to slide longitudinally in a bearing in the keyboard frame and to be normally held in its forward position by a spring 33^a, 80 (see Fig. 1). The connection between the rod 32^a and the lever 29^a is formed by a bifurcation or slot bearing in the end of the lever and a double collar sleeve 34^a mounted on the inner end of the rod. 85

Pivottally mounted, preferably on the shaft 30^a before referred to, is a repeat key rocker frame 36^a with which the inner end of the repeat key bar 37^a is adapted to co-operate to move the rocker frame 36^a rearwardly, whenever the repeat key 15^a is depressed. The rocker frame 36^a is formed with an upwardly extending arm constituting a lever 37^a, preferably arranged parallel with the lever 29^a and having its upper 90 end bifurcated for the reception of the rear end of a stop rod 38^a. Said rod is provided on its inner end with an adjustable collar or shoulder 38^b, whereby a rear or inward movement of the lever will effect a corresponding movement of the rod. 100

At their forward ends the rods 32^a and 38^a are connected by a trip bar in such a way that advance movement of rod 38^a will cause a corresponding movement of rod 32^a. The 110 tripping of this bar may be accomplished by any suitable mechanism (not shown) preferably under the control of the line scale rack 14, for automatically stopping the repeat mechanism. A suitable mechanism of 110 this kind is set forth in the pending application of Bancroft, Indahl and Hofberg, Serial No. 62,611; filed November 20th, 1915, now Patent No. 1,220,058, dated March 20, 1917. Other stop mechanisms are disclosed 115 in Patents No. 1,106,538 and No. 1,149,232, but it is to be understood that for the purposes of this invention any suitable repeat mechanism may be employed whether or not it is equipped with an automatic stop device. 120

As has been hereinbefore stated, the repeat bar 19^a is normally held in elevated position against the stops 19^b by the latch 27^a on the plate 28^a; this latch cooperates in the mechanism shown in Figs. 1-7, inclusive, 125 with the projection 40^a on the bar. The plate and latch are normally positioned against the stop bracket 41^a secured to the frame 23^a by the screws 42^a, due to the action of the springs 33^a and 43^a or either of them. 130

- One end of the last mentioned spring is secured to a fixed part of the machine as the frame 23^a, by means of the pin 44^a, the other end being secured to the pin 45^a, laterally extending from the plate 28^a. In this normal position of these parts the pin 45^a rests against the downwardly projecting portion 46^a of the justification control valve bar 50 (Figs. 3 and 7) and thus normally maintains said valve bar in advanced position as shown in Fig. 3. In such position the end of the valve bar 50 engages with the stem of the justification control valve 51 and maintains the valve head off its seat so as normally to maintain an open communication for the air under pressure between the air chamber 161 and the pipe 117 leading to the motor or motors associated with the justification indicating device.
- Normally, then, the repeat motor is held from operation by the latch 27^a coöperating with the projection 40^a on the repeat bar 19^a, another part of the repeat bar, namely, the arm 24^a, extending between and maintaining inactive the pistons in the repeat cylinders 25^a and 26^a. When any of the keys 180 are depressed the composing machine will operate in the usual manner; within the justification area the motor piston 4' advances the abutment slide 9^a, such movement being against the opposition formed by air under pressure in the cylinder 12, and this is followed by the rotation of the justification indicator and the corresponding movement of the pin 19 until the latter comes against the projection 115 of the slide 9^a in its new or displaced position.

When it is desired to repeat the signals of a desired character in the record strip, the key representing such character and also the repeat key 15^a are depressed. The latter key causes an advance of the repeat key bar 37^a which rotates the rocker frame 36^a upon its shaft 30^a so as to operate the lever 37^b and by it advance the rod 38^a. The latter causes the rod 32^a to advance also, because of the trip bar connection between these rods (as in said Patent No. 1,220,058), and the rod 32^a rocks the arm 29^a and the plate 28^a secured thereto away from the stop 41^a, this movement being against the tension of the springs 33^a and 43^a. The rocking of the plate 28^a removes the latch 27^a from the projection 40^a on the repeat bar 19^a so as to allow the repeat motor to operate said bar, and also moves the pin 45^a from its normal position in which it holds the justification control valve bar 50 advanced. The latter and the justification control valve 51 are retracted because of the air pressure in chamber 161 acting upon the valve head, and the communication between said chamber 161 and the pipe 117 is closed. During the opera-

tion of the repeat motor, therefore, the air motor elements of the justification indicating mechanism are cut off from their source of air under pressure and are exhausted to the atmosphere. There is no operation of these parts while the repeat key is down and there is no resistance opposed to the operation of the line measuring mechanism to influence the proper operation of the same.

Upon releasing the repeat key 15^a the parts moved by its depression are returned to their normal positions, the latch 27^a locking the bar 19^a against operation and the pin 45^a advancing the justification valve 50 control bar 50 and its valve 51 to establish normal communication between the justification devices and the air chamber 161. Thus at the end of the repeat operation air is admitted to the cylinders 12 and 25 and the abutment slide 9^a, the gaging number 9 and the indicator 8 are moved, if necessary, to the position in which the slide rests against the motor piston 4', the parts 19 and 114 rest against the portion 115 of the slide and the indicator is in position corresponding to the position of these parts.

It will be understood of course that the depression of any character key will advance one or more of the valve bars 173 and 95 that when the repeat bar 19^a is in motion the bell cranks 18^a of the advanced bars 173 will oscillate to cause the rapid opening and closing of the corresponding valves 170. This repetition in the operation of these 100 valves will cause the usual operation of the punch mechanism, paper feed mechanism, line measuring mechanism and other mechanisms of the composing machine which operate in accordance with the operation of 105 valves 170.

In the modification shown in Fig. 8 the pin 45^a and coöperating projection 46^a of the justification control valve bar 50 are dispensed with and instead of the justification control valve 51 which is similar in construction to the ordinary valves 170, there is used a justification control valve of slightly different structure such that communication is maintained between the 115 chamber 161 and the pipe 117 when the valve is in its normal retracted position and such communication is cut off when the valve is advanced. In this modified construction the valve bar 50 is provided with 120 an upwardly projecting part 52 the rearward portion of which rests against the pin 53 laterally projecting from the upwardly projecting arm 54 integral with the plate 28^a. The justification control valve 55 has 125 a reduced inner end 55^x so that when its stem rests against the end of valve bar 50 in retracted position, there is free passage between the chamber 161 and the pipe 117; when, however, the bar and its valve are 130

advanced this connection is broken and the pipe 117 is placed in communication with the atmosphere. The justification control valve 55 and its valve bar 50 are advanced 5 by the advance of the repeat key bar 37^a which rocks the frame 36^a and its lever 37^b through which and the trip bar the lever 29^a and the plate 28^a are rocked, as described in connection with the mechanism 10 of Figs. 1 to 7, inclusive, and with the plate 28^a is moved the arm 54 and the pin 53 secured thereto, so as to coöperate with the rearward portion of the projection 52 and advance the bar 50.

15 In both of the above constructions it will be noted that the justification valve is normally open so as to maintain air under pressure in the cylinders of the motors associated with the justification indicating mechanism.

20 The operation of the repeat mechanism, however, automatically closes the said valve and exhausts said cylinders; thus, the advance of the line measuring mechanism within the 25 justification area meets with no appreciable resistance due to the justification indicating mechanism and transmits none of its motion to such mechanism. Upon the stopping of the repeat mechanism, air pressure will be at once admitted to the justification indicating 30 motor and the abutment slide and associated parts will thereby be moved until the pin 19 is against its stop 22 or until the slide is against the piston 4.

When in the specification and claims I refer to the justification indicating mechanism or parts thereof as being "inactive," I mean that such mechanism or its parts do not perform their functions of indicating proper justification, although, in some cases, there 40 may be an actual movement of such mechanism or some of its parts.

What is claimed is:

1. A typographic composing machine embodying a repeat mechanism, an automatic 45 justification indicating mechanism and means for automatically rendering the justification indicating mechanism inactive while the repeat mechanism is in operation.

2. A typographic composing machine embodying a repeat mechanism, an automatic justification indicating mechanism provided with a motor and means operated by said repeat mechanism for rendering said motor 50 temporarily inactive.

55 3. A typographic composing machine embodying a repeat mechanism, provided with a manually controlled actuating mechanism, an automatic justification indicating mechanism provided with a motor, and means operated in unison with said actuating mechanism for rendering said motor inactive.

4. A typographic composing machine embodying a repeat mechanism having an air pressure motor, an automatic justification indicating mechanism having an air pressure 60

motor, and means for rendering said last mentioned motor inactive while said repeat mechanism is in operation.

5. A typographic composing machine embodying a repeat mechanism having an air 70 pressure motor, an automatic justification indicating mechanism having an air pressure motor, and means operated by said repeat mechanism for rendering said last mentioned motor inactive. 75

6. A typographic composing machine embodying a repeat mechanism provided with an air pressure motor and a manually controlled actuating mechanism, an automatic justification indicating mechanism having 80 an air pressure motor, and means operated by said actuating mechanism for rendering said last mentioned motor inactive.

7. In a typographic composing machine including key controlled signal producing 85 and line measuring mechanism and justification indicating mechanism adapted automatically to follow up the movements of said line measuring mechanism within the justification area, and in combination therewith, 90 means for causing an automatic repetition of the operation of the signal producing mechanism for an operated controlling key, and means connected with said repeating means and with said justification indicating 95 mechanism for rendering the latter inactive while the former is in operation.

8. In a typographic composing machine including key controlled signal producing mechanism, a repeat mechanism, automatic 100 justification indicating mechanism comprising an indicator and a motor for operating the same, and in combination therewith, means operated by said repeat mechanism for rendering said motor inactive. 105

9. In a typographic composing machine including key controlled signal producing mechanism and line measuring mechanism, a repeat mechanism, automatic justification indicating mechanism comprising an abut- 110 ment slide adapted to be advanced by said line measuring mechanism, a motor for returning said abutment slide, an indicator and a motor for operating said indicator to a position determined by said abutment slide, and in 115 combination therewith, means operated by said repeat mechanism for rendering said indicator operating motor inactive.

10. In a typographic composing machine including key controlled signal producing 120 mechanism and line measuring mechanism, a repeat mechanism, automatic justification indicating mechanism comprising an abutment slide adapted to be advanced by said line measuring mechanism, an air pressure 125 motor for returning said abutment slide, an indicator and a motor for operating said indicator to a position determined by said abutment slide, and in combination therewith, means operated by said repeat mecha- 130

nism for relieving said air pressure motor of air under pressure.

11. In a typographic composing machine including key controlled signal producing mechanism and line measuring mechanism, a repeat mechanism, automatic justification indicating mechanism comprising an abutment slide adapted to be advanced by said line measuring mechanism, an air pressure motor for returning said abutment slide, an indicator, and an air pressure motor for operating said indicator to a position determined by said abutment slide, and in combination therewith, means operated by said repeat mechanism for relieving both of said motors of air under pressure.

12. In a typographic composing machine including key controlled signal producing and line measuring mechanism, automatic justification indicating mechanism provided with an air pressure motor, repeat mechanism comprising an air pressure motor, a latch device for controlling the operation of said repeat motor, a repeat key and means operated by said repeat key for operating said latch device, and in combination therewith a valved conduit connecting said justification indicating mechanism motor with a source of air under pressure, said valve being controlled by said latch device, whereby when said latch device is operated by the repeat key said justification indicating mechanism motor is relieved of air under pressure.

13. In a typographic composing machine including key controlled signal producing and line measuring mechanism, automatic justification indicating mechanism comprising an abutment slide adapted to be advanced by said line measuring mechanism, an air pressure motor for returning said

abutment slide, an indicator and a motor for operating said indicator to a position determined by said abutment slide, a repeat mechanism comprising an air pressure motor, a latch device for controlling the operation of said repeat motor, a repeat key and means operated by said repeat key for operating said latch device, and in combination therewith, a valved conduit connecting said abutment slide return motor with a source of air under pressure, said valve being controlled by said latch device, whereby when said latch device is operated by the repeat key said abutment slide return motor is relieved of air under pressure.

14. In a typographic composing machine including key controlled signal producing and line measuring mechanism, automatic justification indicating mechanism comprising an abutment slide adapted to be advanced by said line measuring mechanism, an air pressure motor for returning said abutment slide, an indicator and an air pressure motor for operating said indicator to a position determined by said abutment slide, a repeat mechanism comprising an air pressure motor, a latch device for controlling the operation of said repeat motor, a repeat key and means operated by said repeat key for operating said latch device, and in combination therewith a valved conduit connecting both said abutment slide return motor and said justification indicating mechanism motor with a source of air under pressure, said valve being controlled by said latch device, whereby when said latch device is operated by the repeat key both said abutment slide return motor and said justification indicating mechanism motor are relieved of air under pressure.
